UNITED STATES PATENT OFFICE.

MAXWELL ALPERN, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

AIR-BACK FOR STOKERS.

1,343,702.

Specification of Letters Patent. Patented June 15, 1920.

Application filed November 2, 1916. Serial No. 129,170.

To all whom it may concern:

Be it known that I, MAXWELL ALPERN, a citizen of the United States, residing in Philadelphia, Pennsylvania, have invented 5 Air-Backs for Stokers, of which the following is a specification.

One object of my invention is to provide a novel means for cooling and thus in a large measure preventing clinkers adhering to the 10 bridge wall or equivalent structure adjacent the ash pocket and ash discharging mechanism of stokers especially of the inclined underfeed type;—the invention contemplated 15 an arrangement of parts whereby air under appreciable pressure is caused to flow over and cool certain structures facing or covering at least one wall of such ash pocket.

I further desire to provide a novel form 20 of air back for apparatus of the class noted, so arranged as to utilize the air in cooling the ashes and clinkers in the ash pocket, as well as for aiding in the combustion of any 25 unburnt fuel which may be mixed with or delivered to the top part of the ashes in said pocket.

A further object of the invention is to provide a novel form of air cooled lining for an ash pocket or facing for a bridge wall which shall be of such construction as to 30 minimize the likelihood of injury by reason of expansion and contraction, and which shall be so disposed as to materially increase the operating and thermal efficiency of the apparatus with which it is employed.

These objects and other advantageous 35 ends I secure as hereinafter set forth, reference being had to the accompanying drawings, in which,

Figure 1 is a vertical section illustrating 40 a boiler equipped with my invention;

Fig. 2 is a vertical section on an enlarged scale illustrating my invention as applied to a furnace similar to that shown in Fig. 1;

Fig. 3 is a horizontal section on the line 45 3—3, Fig. 2;

Figs. 4 and 5 are respectively front and side elevations of one of the air back sections;

Figs. 6 and 7 are vertical sections taken on 50 the lines 6—6 and 7—7, Fig. 4;

Figs. 8 and 9 are transverse sections on the lines 8—8 and 9—9, Fig. 7; and

Fig. 10 is an end elevation of the structure shown in Fig. 4.

55 In the above drawings, 1 represents the

furnace of a boiler having a bridge wall 2 and supplied with fuel by a stoker 3 of the inclined underfeed type. The lower section 4 of the grate of this stoker is spaced away from the adjacent portion of the bridge wall 60 to form a relatively deep transversely extending ash pocket 5 having at one side of its lower portion angularly adjustable ash confining plates 6 and provided at its bottom with an ash crushing and discharging member 7 consisting of a rotary structure having projecting blades or teeth. The ashes crushed by and discharged between the rotary structure and the lower portions of the plates 6 fall into a sealed ash pit 8. 70

According to the present invention there is set in that portion of the bridge wall 2 which forms one side of the ash pocket 5, a series of vertically corrugated facing sections 9 held in place, and so arranged that 75 their lower ends are removably bolted as shown in Fig. 2, to a transversely extending member 10 mounted in the bridge wall, while their upper ends are provided with a pair of projecting lugs or fingers 11 projecting 80 back of a second transversely extending member 12 also embedded in the bridge wall structure;—the arrangement being such that the loosening of the bolt 13 of any section 9 will permit its lower end to be swung out 85 into the ash pocket, whereupon it may be drawn downwardly until its lug 11 is free from the retaining member 12, which in the present instance is provided by the flange 90 of a channel section.

As shown in Figs. 4, 6 and 7, the lower end of each section has perforations 14 formed in the outer parts of its corrugations and in addition the lower ends of the sections are spaced away from the adjacent 95 part of the bridge wall structure so that air flowing vertically downward through said corrugations can to some extent escape through the perforations 14, although the greater portion is free to pass out of the 100 lower ends of the corrugations and into the ash pocket through this space or opening 15.

For supplying air to the air back formed by these corrugated sections, I provide in 105 the bridge wall a passage 17 extending transversely of the stoker and connected through a suitable passage 18 to an air conduit 19 supplied with air from the air conduit 20 ordinarily delivering to the wind box 21 110

of the stoker. In Fig. 1, I have shown the construction adopted when both the air back and the wind box supply conduit are fed from a common source, the passage 17 in 5 the bridge wall 2 being connected by a conduit 18^a with a transversely extending trunk or air reservoir 19^a connected by a conduit 19 to the wind box supply conduit 20^a.

- 10 With the above described arrangement of parts the air delivered to the transversely extending passage 17 flows into the upper ends of the corrugated sections constituting the air back, and passes down through these 15 latter to their lower ends where it escapes through the openings 14 and 15 into the lower part of the ash receiving pocket immediately adjacent the discharge apparatus thereof. This air thus not only cools the air 20 back sections 9 so as to prevent the adhering of ashes and clinkers thereto, but acts to cool the ashes in the pocket, being necessarily required to flow upwardly through the latter in view of the fact that the ash pit 25 is sealed or air tight.

In thus flowing, the air is heated and insures the complete combustion of any unburnt material which may be present among the ashes. Moreover with the above described 30 arrangement, the stoker mechanism may be so operated that unburnt fuel is delivered on top of the ashes in the upper part of the ash pocket and this likewise may be economically burnt with the highly heated air flowing upwardly through it.

As will be understood by those skilled in the art, the ashes accumulating in the pocket are continuously or intermittently discharged into the ash pit by the rotation of 40 the crushing or discharging member 7, which may obviously be operated at a higher speed than has hitherto been permissible since such ashes are cooled in a comparatively short time.

45 With the construction illustrated the corrugations of the air back sections soon become filled with a protecting body of ashes and this, with the cooling effect of the air flowing over their rear or inner surfaces, 50 serves to effectually protect them from injury as well as to prevent to a large degree, clinkers fusing to them. Moreover, owing to the corrugated construction, very considerable expansion and contraction of the various 55 sections may occur without cracking or other injury to them and their associated parts.

In that form of the invention shown in Fig. 1, I have illustrated guiding structures 25 mounted in the ash pocket below and in 60 continuation of the air back sections 9, for the purpose of positively directing the downwardly moving body of ashes and clinkers toward and into engagement with the rotary discharging device 7.

65 I claim:

1. The combination in an inclined, under-feed stoker of a furnace including two structures defining an elongated, horizontally extending ash pocket; means for discharging 70 ashes from said pocket; a corrugated plate mounted on one of said structures; and means for delivering air under pressure to the rear face of said plate.

2. The combination in an inclined, under-feed stoker of a furnace including two structures defining an elongated, horizontally extending ash pocket; means for discharging ashes from said pocket; with a corrugated plate mounted on one of said 80 structures and having air spaces adjacent its rear face.

3. The combination of an inclined under-feed stoker; a bridge wall coöperating therewith to form a transversely extending ash 85 pocket; means for discharging ashes from said pocket; a sectional vertically corrugated plate having the sections removably mounted on said bridge wall within the pocket; and means for delivering air under pressure 90 to the rear face of the plate.

4. The combination of an inclined under-feed stoker; a bridge wall coöperating therewith to form a transversely extending ash pocket; means for discharging ashes from 95 said pocket; a sectional vertically corrugated plate having its sections mounted on said bridge wall within the pocket; and means for delivering air under pressure to the rear face of the plate, there being openings 100 through the lower portion of the plate for delivering air into the ash pocket.

5. The combination in a furnace of a stoker; a bridge wall coöperating therewith to form an ash pocket; means for discharging 105 ashes from said pocket; a plate mounted on said bridge wall within the pocket; means for supplying air under pressure to cool said plate; with a guide plate mounted between the ash discharging means and the lower 110 portion of said first plate for directing ashes toward said ash discharging means.

MAXWELL ALPERN.
